DESIGN FOR A COOK STOVE

Norman F. Heym, Owosso, Mich., assignor to
Renown Stove Company, a corporation of
Michigan

Application January 30, 1939, Serial No. 82,663

Term of patent 3½ years

To all whom it may concern:

Be it known that I, Norman F. Heym, a citizen of the United States, residing at Owosso, in the county of Shiawassee and State of Michigan, have invented a new, original, and ornamental Design for a Cook Stove, of which the following is a specification, reference being had to the accompanying drawing, forming a part thereof.

Fig. 1 is a perspective view of a cook stove showing my new design with the stove lid cover removed; and

Fig. 2 is a similar fragmentary view showing the stove lid cover in place with the top of the central device on the front right-hand panel omitted.

My design is characterized by the specific top and back guard panel in combination with the particular stove shown.

I claim:

The ornamental design for a cook stove, as shown and described,

NORMAN F. HEYM.
